UNITED STATES PATENT OFFICE.

KATHERINA LIWACZ, OF PHILADELPHIA, PENNSYLVANIA.

ASH-SIFTER.

1,375,575.

Specification of Letters Patent. Patented Aug. 13, 1918.

Application filed January 26, 1917. Serial No. 144,709.

To all whom it may concern:

Be it known that I, KATHERINA LIWACZ, a subject of the Emperor of Austria, residing at Philadelphia, in the county of Philadelphia and State of Pennsylvania, have invented certain new and useful Improvements in Ash-Sifters, of which the following is a specification.

This invention relates to ash sifters and has special reference to an ash sifter so designed and arranged as to prevent dust from the ashes finding its way to the exterior of the sifter where it will settle on surrounding objects.

One important object of the invention is to provide an improved general construction for ash sifters of this character.

A second important object of the invention is to provide an improved construction of ash sifter arranged to be directly connected with the ash pit of a stove or range.

A third important object of the invention is to provide an ash sifter of this description with check or baffle means to prevent the passage of the dust from the ashes upward to the stove where they would be apt to find their way outside and create dust in the kitchen or other room in which the stove is located.

A fourth important object of the invention is to provide an improved arrangement for disposing of the cinders after the cinders and ashes have been separated.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:—

Figure 1 is a side elevation partly in section and showing the improved ash sifter connected to the ash pit of a stove or other like device.

Fig. 2 is a plan view of the sifter.

Fig. 3 is a section on the line 3—3 of Fig. 1.

Fig. 4 is a vertical median section through the body of the sifter.

Fig. 5 is a section on the line 5—5 of Fig. 4.

Fig. 6 is a detail section taken longitudinally of the pipe leading from the ash pit

to the body of the sifter and showing the arrangement for checking the upward passage of the dust.

Fig. 7 is a section on the line 7—7 of Fig. 6.

Fig. 8 is a section on the line 8—8 of Fig. 1.

In the drawings illustrating one preferred embodiment of the invention there has been shown the floor F of a building whereon is disclosed a portion of a stove S having an ash pit 10. Leading downward from the ash pit 10 is an inverted frusto-conical hopper 11 having at its lower end a flexible and rotatable joint diagrammatically indicated at 12. Connected to this joint is a pipe or chute 13 having an elbow 14 at its lower end which is connected to the top 15 of a casing 16. Mounted on standards 17 is a hopper 18 the lower end of which is of inverted frusto-conical form. The lower end of this hopper is furthermore closed by a hinged door 19 secured by a suitable latch 20 in its closed position. The casing 16 is surrounded at its upper end with a ring 21 carrying resilient arms 22 the lower ends of which engage, when the device is assembled, in notches 23 formed on the standards 17 so that by this means the casing and standards are held in proper correlated position. At 24 is an oscillatory shaker member provided with a foraminous floor 25 and this shaker member closely surrounds the lower end of the casing 16 within the hopper 18. Furthermore, the upper edge of the hopper 18 is flanged as at 26 and in like manner the upper end of the member 24 is provided with a flange 27 which rests on the flange 26 so that the shaker member can be rotated with respect to the casing 16 and hopper 18.

In order to effect this rotation there is provided in the wall of the hopper 18 a slot 28 wherethrough passes an arm 29 provided on its outer end with a handle 30, the arm being connected to the shaker member 24.

Now, in the operation of the device, as thus far described the ashes will pass down from the ash pit through the small hopper 11 and the chute 13 into the casing 16 where they will be received on the bottom of the shaker member 24. Then, by oscillating the handle 30, the shaker member will be oscillated and the fine ashes will sift through the foraminous bottom 25 into the hopper 18 while the cinders will be retained in the

shaker member. After sufficient ashes have accumulated in the hopper 18 a suitable receptacle such as an ash can, wheelbarrow, or the like may be placed beneath the door 19 and the latter opened so that the ashes will drop into the receptacle which may then be carried away to any convenient place of deposit.

In order to dispose of the cinders which are in the shaker member this shaker member is provided on its side with an opening which is normally kept closed by a sliding door 31 having a finger grip 32 at its upper end. At one point in the wall of the hopper 18 is formed an opening 33 from whence leads a chute 34 the bottom of which projects inward into the hopper to form a lip 35 whereon the bottom of the shaker member rests. The door 31 and opening 33 are so correlated with the slot 28 that when the arm 29 is at one extreme position in this slot the door 31 will be opposite the opening 33 so that by pulling up on the finger grip 32 communication is established between the interior of the shaker member and the chute 34. In order to force the cinders out through the opening thus made there is provided a vertical shaft 36 which extends axially of the shaker member and carries on its lower end a curved blade 37 wider at its outer end than at the part adjacent the shaft 36 and the outer end of this blade is located closely adjacent the side wall of the shaker member 24. On the upper end of this blade is a crank handle 38 by means of which it may be rotated and it will be seen that when the blade is rotated in the direction of the arrow in Fig. 3 the cinders on the bottom or floor of the shaker member will be pushed outward toward the periphery of this member and carried around until they are pushed out of the door opening so that they may fall downward through the chute 34 and be received in a suitable bin or other receptacle for use in the stove.

This operation of shaking and separating the ashes from the cinders is of course attended with a very considerable amount of dust which would ordinarily rise through the pipe or chute 13 but this is prevented in the following manner. In the upper end of this pipe 13 there is fitted an inverted frusto-conical nozzle 39 which is axially arranged in the pipe 13 and below this nozzle 39 is arranged a hollow cone spreader 40 supported by a spider 41. Now the mixed ashes and cinders will pass downward through the nozzle 39 and be spread by the spreader 40 but when the dust tends to pass upward part of the dust will pass into the hollow conical spreader 40 and be there checked and dropped back while the remainder of the dust will tend to follow the arrow heads in Fig. 6 and be checked by

the wall of the nozzle 39 so that practically all of the dust will be prevented from passing upward into the ash pit and thus finding its way out into the room.

In order to support the shaft 36 the top 70 15 is provided with a small bearing spider 42.

In the continuation of the operation of the device, after the cinders and ashes have been separated, the handle 30 pushed as far 75 to the right as possible which will bring the door 31 opposite the opening 33. Then by opening the door and rotating the shaft 36 the cinders are pushed out and fall down the chute.

There has thus been provided a simple and efficient device of the kind described and for the purpose specified.

It is obvious that many minor changes may be made in the form and construction 85 of the invention without departing from the material principles thereof. It is not therefore desired to confine the invention to the exact form herein shown and described but it is wished to include all such as properly 90 come within the scope claimed.

Having thus described the invention, what is claimed as new, is:—

1. In an ash sifter of the class described, a hopper, an oscillatory shaker member supported within the hopper and having a foraminous bottom, a closure casing removably carried by the hopper structure and telescoping within the shaker member, means suspended from the closure casing to rotate independently of the shaker member to throw the cinders to the side of the shaker, an outlet through the walls of the hopper and shaker to lead the cinders away and a closure in the bottom of said hopper.

2. In an ash sifter, a hopper having a flanged seat formed around its top edge, an oscillatory shaker having an outturned flange upon its upper edge and rested on said flanged seat, so that the shaker is supported within the hopper solely from said seat, said shaker furthermore having a sifter bottom, a closure casing removably carried by the hopper structure and telescoping within the shaker member, means suspended from the closure casing to rotate independently of the shaker member to throw the cinders to the side of the shaker, and an outlet through the walls of the hopper and shaker to lead the cinders away.

3. In an ash sifter, a hopper having a flanged seat formed around its top edge, an oscillatory shaker having its upper edge outwardly flanged and rested on said flanged seat, so that the shaker is supported within the hopper solely from said seat, a closure casing carried by the hopper structure and telescoping within the shaker member, a series of spring arms carried by the casing and overlying the outside of the hopper

structure and locking elements on the hopper structure to be engaged by the casing whereby the latter is removably held and locked.

- 5 4. In an ash sifter, a hopper having a flanged seat formed around its top edge, a shaker structure having a cylindrical wall whose upper edge is outturned into a supporting flange bearing on said seat and rotatable thereon, a closure casing removably carried by the hopper and telescoping closely within the cylindrical wall of the shaker structure, a rotary blade removable
- 10 with said closure casing, and active above the bottom of the shaker structure to throw 15 the cinders to the side of the latter, a cinders removing chute entered into the wall of the hopper and communicative with an outlet in the wall of the shaker structure, and a door vertically removable from one of said 20 outlets.

In testimony whereof I affix my signature.
